UNITED STATES PATENT OFFICE.

ALEXANDER J. MACLEAN, OF NEW YORK, N. Y.

MEANS FOR LOCKING OR UNLOCKING RUDDERS.

SPECIFICATION forming part of Letters Patent No. 752,086, dated February 16, 1904.

Application filed November 13, 1903. Serial No. 181,006. (No model.)

To all whom it may concern:

Be it known that I, ALEXANDER J. MACLEAN, a citizen of the United States, and a resident of New York, in the county of New York and State of New York, have invented certain new and useful Improvements in Means for Locking or Unlocking Rudders, of which the following is a specification.

The present invention relates to means for locking and unlocking the rudders of boats, and more especially boats having rudders at both ends, one of the prominent objects of the invention being to insure the positive locking and also permit the unlocking of either rudder from a relatively remote point or station on the boat.

Another object is the disposition of those parts which more immediately coact with each rudder-post to lock and unlock the same, so that such parts will not be subject to interference by reason of freezing up or on account of improper position of the rudder. Positiveness and facility of actuation of the connections controlling the locking devices more nearly adjacent to each rudder-post also constitutes an important feature.

With the above and other purposes in view the invention comprises a boat having a rudder at each end and equipped with rudder locking and unlocking means, such means including a bolt or engaging element conditioned to be so controlled that in the locking operation the bolt or element will automatically attain its rudder locking or engaging relation only when the rudder to which it more especially appertains shall occupy a longitudinal position with respect to the boat. In so far as this feature is concerned it will be generally applicable for rudder-locking purposes. For reasons previously intimated the rudder locking and unlocking devices are preferably so located as to be protected from undesirable or accidental interference by virtue of their in-board position. The connections for actuating the locking and unlocking parts more nearly adjacent to the rudder-post are of a character insuring their positive working as well as conduceing to ease of operation.

There are other important features connect-
ed with the invention which besides those al-

luded to are clearly set forth in the subsequent detailed description.

In the accompanying drawings, forming part of this specification, Figure 1 is a diagrammatic plan view illustrating the general arrangement and disposition of the improved locking and unlocking means applied to a boat having a rudder at both ends. Fig. 2 is a vertical sectional detail view of one of the end portions of a boat and showing particularly the relation of the locking and unlocking parts more immediately coacting with the rudder. Fig. 3 is a central vertical detail sectional view, on an enlarged scale, of the deck at one end of the boat and disclosing certain of the locking and unlocking devices. Fig. 4 is a detail view illustrating the arrangement of lever and immediate connections for effecting the locking and unlocking operations. Figs. 5 and 6 are views somewhat similar to Fig. 3, but illustrating other arrangements of the locking and unlocking parts adjacent to one of the rudders.

Similar reference characters are employed to designate corresponding parts in the several figures of the drawings wherein they occur.

The boat will of course be equipped with suitable steering gear or devices, the illustration of which in view of the character of the present invention has been regarded as unnecessary, and is therefore omitted.

As indicated in Fig. 1, a rudder-post A turns in suitable bearings at each end of the boat, it being understood that each post carries a rudder beneath the overhang at that end of the hull where said rudder is located. As will be noted by reference to Fig. 2, a chamber or clearance is provided at each end below the deck C, in which chamber the post of the rudder B is mounted, and to the upper extremity of said post is the hub d of a horizontal quadrant-shaped metal frame D, occupying a position a short distance below the deck. This quadrant is located at the inner side of its post, and its arc portion is presented by a horizontal curved plate d', having a relatively-extended vertical outer face. This bar contains at a mid-point a horizontal opening d'', which at its outer end has a flaring or conical mouth d''. (See Fig. 3.)

From one of the deck-beams c depends a

hanger E, which is enlarged at its lower portion to present a boss e, having a horizontal opening located in a horizontal plane common with that of the opening d'.

Suspended from certain of the deck-beams at each end of the hull are suitable guides f f, each of which is adapted for sustaining and permitting the longitudinal movements of a horizontally-extended rod F. This rod, as well as other rods to be presently referred to and which perform similar functions, is preferably composed of suitable lengths of tubing, which are pinned together at their adjacent ends. That extremity of the rod F which is contiguous to the hanger E is provided with a horizontal locking bolt or pin G, the free end of which bears and is supported in the opening of the boss e. I prefer that the extremity g of this bolt shall be slightly tapering or conical.

By again referring to Fig. 1 it will be observed that the positions of two pilot-houses H H' are illustrated by dotted lines. It will also be noted that the rod F extends longitudinally to a point somewhat in the vicinity of the pilot-house H, where said rod is connected with one of the members of a bell-crank lever I, the other member of which has attached thereto the inner end of a shorter rod F', transversely disposed, as illustrated. The other end of this rod F' is connected with one of the members of a bell-crank lever I', the other member of which has pivotally attached thereto a longitudinal rod F² of the extended character represented. This rod is of such length that its other extremity is pivotally secured to one of the members of a bell-crank lever I², oppositely located at one side of the pilot-house H', the other member of said bell-crank lever having pivotally connected therewith a short transverse rod F³, extending within the pilot-house last mentioned. The several rods F', F², and F³ are slidably supported in guides depending from below the deck and similar in character to those already described, the brackets for sustaining the bell-crank levers being also suitably connected at the under side of the deck. The rudder-post A at the opposite end of the boat also carries a rudder and is located within a chamber similar to that previously explained, said rudder-post having secured thereto a quadrant-shaped frame D', containing a central opening in a horizontal plane common with the opening in a hanger arranged similar to the hanger E and in corresponding coactive relation. A rod J is suspended in suitable guides at the under side of the deck and carries at its free extremity a locking bolt or pin designed to perform the same functions with respect to the frame D' as does the bolt G with respect to the frame E. The rod J is operably connected with the pilot-house H through the medium of bell-crank levers K, K', and K² and rods J', J², and J³, arranged in a manner similar to the rods

and bell-crank levers previously described, but obviously in the reverse relation illustrated.

As the disposition and character of certain parts within the pilot-house H' are the same as the corresponding parts within the pilot-house H, a description of such parts within one of the houses will suffice for an understanding of both.

By reference to Fig. 4 it will be seen that the inner end of the rod F³ is connected to one of the members of a bell-crank lever I³, pivotally supported below the deck-beams, the other member of said bell-crank lever having pivotally attached thereto the lower extremity of a vertical rod F⁴, movable in appropriately-located guides h below the floor of the pilot-house. The upper end of said rod F⁴ is pivotally connected to one of the members of a bell-crank lever I⁴, pivotally supported a short distance below the floor h' of the pilot-house, the other member of said lever being connected by a link i with the lower end of a lever L, pivoted in a bracket l, secured on the bottom of said floor, the lever above said bracket extending through a suitable opening in the floor in a position convenient for operation by the pilot. Secured on the floor is an arched guide l', having stops or lugs adapted to be engaged by the lever and retain the same in either of the two positions to which it may be thrown at each side of a central position.

From the description thus far it will be readily understood that a pilot before leaving the pilot-house H' locks the rudder B accurately in a longitudinal position. This is accomplished by throwing the lever L to the "in" position and engaging the same with the lug thereat, so as to retain said lever as thus thrown. The movement of the lever referred to will, through the medium of the rod and bell-crank lever connections, have a tendency to project the bolt or pin through and beyond the perforation in the boss e. If, however, the rudder D is not accurately in a longitudinal position, the lever cannot be moved to its full extent in the desired direction, inasmuch as the extremity of the bolt will be in contact with an imperforate portion of the curved plate d' of the frame D. The pilot, however, maintains the position of the lever to the limit of the inclined position permitted until the rudder has moved to an extent resulting in the frame perforation d' coming into longitudinal alignment with the opening in the boss, whereupon, as will be manifest, the lever will complete its movement of inclination and the bolt consequently be projected to an extent that will result in its becoming engaged within the perforation of the frame D. The lever L is located immediately back of the steering-wheel, which enables the pilot to manipulate the lever with one hand while nursing the rudder into a central position. Thus said frame and its related rudder will be locked in a position whereby the latter will be positively held in a strictly lon-

gitudinal position. The flaring character of the mouth of the opening d^2 in the frame D, combined with the tapering end of the bolt, will compensate for any slight relative variation in the positions of the opening of said frame and adjacent hanger, as such flaring mouth and conical end will under such condition permit the bolt end to come to a full-centered position within the opening d^2 . The locking operation of the rudder B having been accomplished, as described, the pilot then leaves the pilot-house H' and enters the pilot-house H, at which time it becomes desirable to release the rudder at the other end, which had been previously locked, as will be understood. The unlocking of said last-mentioned rudder is manifestly accomplished by throwing the lever to the "out" position, which results in the actuation of the several rods and bell-crank connections $J^3 K^2$, &c., and effects the disengagement of the bolt or pin adjacent to the frame D' and the consequent unlocking of the rudder of the same. It will be appreciated that with the locking means conditioned as described the same are not only susceptible of actuation with comparatively little effort on the part of the pilot, but that the rudder can only be locked when in its proper longitudinal position, and, further, that the failure of the actuating connections to respond to their operative limit will positively convey to the pilot knowledge of the fact that the locking operation has not been completed. The importance of this will be fully realized.

The locking and unlocking means may be modified in many particulars and still be within the scope of my invention. For instance, in Fig. 5 I have represented an arrangement whereby one of the connections leading from the pilot-house is presented by a vertical revoluble rod M, supported and sustained in suitable bearings m —say, for instance, by a collar m' —the lower end of said rod having secured thereon a gear-wheel N, meshing with the similar wheel N' on the end of a stub-shaft O, revolving in a suitable hanger o and having a threaded portion o' . This shaft O is restrained from longitudinal movement in its bearing by a collar and setscrew o^2 . Upon the threaded portion of the stub-shaft is a turnbuckle P, adapted through the revolution of said shaft to be advanced or retracted, according to the direction of rotation, the outer end of said buckle being provided with a square bolt p , normally resting within the opening at the lower end of a hanger Q, which, it is to be understood, is in apposite relation with respect to a quadrant-frame having a centrally-located opening, as has heretofore been explained. The rotation of the rod M in one direction or the other will palpably cause the advancement of the turnbuckle and the projection of the bolt to

engage the frame, or retraction of said turnbuckle and disengagement of the bolt, as the case may be.

In Fig. 6 I have shown an arrangement whereby a vertically-disposed sprocket or wire-rope chain R is in gear at its upper end with a wheel (not shown) the rotation of which can be readily effected through suitable connections extending to the appropriate pilot-house. The chain or wire rope R is also in gear with a sprocket-wheel s on the end of a stub-shaft S, revolving in a suitable hanger T, but held against longitudinal movement, the threaded portion s' of said stub-shaft coacting with a turnbuckle U and bolt u in a manner evident from an understanding of the construction disclosed in Fig. 5.

As before intimated, I do not wish to be understood as limiting myself to the constructions and arrangements of parts shown and described, but reserve the right to all modifications that may be within the scope of my invention.

Having now described my invention, what I claim as new, and desire to secure by Letters Patent, is—

1. In rudder locking and unlocking means, the combination with a rudder and a horizontally-movable frame connected therewith and embodying a curved plate containing an opening, of a bolt repressed by said plate at either side of the opening, but adapted to enter the latter and lock the frame when the rudder is in a central position.

2. The combination with a boat and its rudder, of a horizontally-movable part connected with the rudder, a bolt repressed by said part when the rudder occupies a central position, said horizontally-movable part adapted to become engaged and locked by the bolt when the rudder is in a central position, and connections extending to a relatively remote point on the boat for operating the bolt.

3. The combination with a boat and its rudder, of a horizontally-movable frame connected with the rudder and embodying a curved plate containing an opening, of a bolt repressed by said plate at either side of said opening, but adapted to enter the latter and lock the frame when the rudder is in a central position, and connections extending to a relatively remote point on the boat for operating the bolt.

4. In rudder locking and unlocking means, the combination with a rudder and a horizontally-movable frame connected therewith and embodying a curved plate containing an opening with an outer flaring mouth, of a part suitably supported in juxtaposition to said plate and containing an opening, and a bolt movably bearing in the opening of said part and repressed by the frame-plate at either side of its opening, said bolt having a conical free end adapted to enter the plate-opening when the latter alines therewith.

5. The combination with a boat having a rudder at each end, of a horizontally-movable part connected with said rudder, a bolt in apposition to and repressed by each part when the rudder thereof is at either side of a central position but engage and lock said part when said rudder is central, and connections each operable independently of the other, and each extending from one of the bolts to a rela-

tively distant point permitting the operation ^{to} of its particular bolt.

Signed at New York, in the county of New York and State of New York, this 6th day of November, A. D. 1903.

ALEXANDER J. MACLEAN.
